ART OF REFINING SUGAR

George E. Stevens, Denver, Colo., assignor to
 The Western States Machine Company, New
 York, N. Y., a corporation of Utah

Application July 3, 1937, Serial No. 151,772

14 Claims. (Cl. 127—64)

This invention relates to the refining of raw cane sugar or like material and is intended to provide a new method of treatment by which the affination or preliminary stage in the refining of raw sugar is effected with much greater efficiency and economy than has been possible with affination processes heretofore used. This application is a continuation-in-part of my copending application, Serial No. 68,013, filed March 10, 1936.

In the production of refined sugar from sugar cane, it is customary to extract a sugar juice from the cane, concentrate the juice, boil it in vacuum pans to promote the growth of crystals and form a massecuite and then separate the constituents of the massecuite in centrifugal machines. The grain sugar first obtained is known as raw sugar, and it usually contains a considerable quantity of impurities most of which are included in a film or coating adhering to the outside of the crystals, although a small percentage of the impurities is occluded in the structure of the crystals themselves. The polarization of plantation raw sugar usually ranges between 94 and 98 and averages about 96. In order to produce a marketable white, or almost white, sugar from raw sugar it is necessary to subject the raw sugar to further refining processes which serve to remove discoloring impurities.

The first stage of the usual refining process is known as the affination, or "washing", of the relatively impure raw sugar. In the affination process raw sugar is mingled with so-called affination syrup to loosen the impure adherent coating on the crystals and form a magma of sufficient fluidity to be introduced into centrifugals, and the magma thus prepared is subjected to centrifuging operations in which part of the syrup is expelled from the sugar grains by centrifugal force and a washing liquid is applied to the partially cleansed grains so as to complete the removal of adherent syrup.

Prior to my present invention the usual practice has been to employ a thin syrup at a purity of around 80, a dry substance or Brix of about 70 and a temperature well below 120° F. as the affination syrup and to mix this syrup with the sugar in proportions suitable for forming a magma of the necessary fluidity. In some instances a more concentrated affination syrup has been used, which has been heated to temperatures approximating 170° F. before mixture with the raw sugar. The mixing of substantially dry raw sugar with affination syrup in accordance with these conventional practices is accomplished in a long, horizontal, fairly shallow mixing trough in which is located a longitudinal rotatable conveyor and mixer. The sugar and the syrup are fed simultaneously into one end of the mixer trough, and the revolving conveyor and stirrer mixes the mingled solid and liquid and conveys

the resulting magma to an outlet passage at the other end of the trough. Adjacent the outlet passage are located crushing rollers which crush lumps present in the mixture of the two ingredients, and from these rollers the magma drops into a receiving tank above centrifugal machines which tank is provided with mechanical stirrers and a series of chutes or goosenecks leading from the bottom of the tank to the individual centrifugals. The discharge ends of the goosenecks are provided with gates which are opened and closed for the purpose of loading successive charges of the magma into the centrifugals.

The mixing of unsaturated affination syrup with raw sugar in accordance with conventional processes results in dissolving approximately 5-10% of the raw sugar crystals flowing to the centrifugals, and this dissolved sugar is carried off from the centrifugals in the extracted syrup, known as green syrup. A further quantity of the raw sugar, approximately 8-10%, is dissolved by the application of wash water to the sugar in the centrifugals at a stage of the centrifuging cycle when the purging or extraction of most of the green syrup has been effected. For every one thousand tons of raw sugar treated by this process, approximately fifty to one hundred tons of the sugar crystals are dissolved by the affination syrup and an additional amount of approximately one hundred to one hundred and fifty tons is dissolved by the washing in the centrifugals, thus making a total of approximately one hundred and fifty to two hundred tons of sugar carried off in the centrifugal run-off which consists of both the green syrup and wash syrup. It is therefore necessary when using these conventional processes to resort to expensive reprocessing of large volumes of green syrup and wash syrup in order to recover the maximum possible quantity of dissolved sugar which they carry from the centrifugals.

A further objectionable feature of the conventional process is that it requires the use of a very large amount of affination syrup in order to produce a magma of proper consistency for centrifuging, and the resulting large volume of magma requires a longer time for treatment in the centrifugals, thus reducing the capacity of the centrifugal station of the refinery. Furthermore, there is a large amount of green syrup expelled from the centrifugals, which ordinarily must be reprocessed and filtered and subjected to decolorizing treatments at some stage of the subsequent treatments to recover a further portion of its sugar content. When following the conventional processes these large volumes of materials are necessarily present. Still another characteristic of conventional affination processes is that wide variations occur in the quality of the syrups purged from the magma in the centrifugal ma-

chines and in the quality of the washed sugar obtained from these machines. Affination syrups available in the refineries for mingling with raw sugar vary considerably in purity and dry substance. Such variations, together with the inability to maintain accurate control over the operation of the usual process, make it impossible to maintain a magma of constant or approximately constant purity and dry substance from hour to hour or from day to day, and non-uniformities in the qualities of the magma prevent optimum performance during loading, purging and washing operations at the centrifugal stations. Aside from the inefficiency inherent in this system, the production of syrups and washed sugar of varying qualities makes it extremely difficult to adjust other refinery operations for best operating results.

An object of my invention is to provide an improved affination process which enables the removal of adherent surface impurities from grain sugar with much smaller quantities of affination syrup than used heretofore, reduces the amount of magma necessary to be centrifuged in the affination of a given amount of sugar, thereby increasing the capacity of equipment used in the process, increases the purity and yield of affined sugar obtained from relatively impure sugar, and permits more flexible control over the entire affination stage of refining.

Another object of my invention is to provide an affination process which continually, day after day, produces (1) washed sugar of substantially uniform and relatively high purity, (2) syrup of substantially uniform purity and dry substance, composed of green and wash syrups, which may be reused in the affination of additional raw sugar to keep the magma produced in the process as constant as possible, and (3) excess wash syrup of substantially uniform and high purity, which may be treated economically and efficiently to produce marketable sugar therefrom.

Another object of the invention is to provide an affination process which makes it possible to produce washed sugar of higher purity than heretofore while using affination syrup of much lower purity and in much smaller quantities than heretofore.

Another object of the invention is to eliminate the necessity for reprocessing large volumes of green and wash syrups, carrying large amounts of impurities that are reprocessed to recover sugar values therein when following customary practices and to corral practically all impurities in a single syrup that is used again and again, thus effecting important savings in filtering, decolorization and other processing costs.

Another object of the invention is to provide an affination process which may be maintained in continuous operation over a long period of time without requiring additions of syrup and at the same time to produce cleansed sugar of uniform and high purity.

I have found that the foregoing and other desirable objects may be attained by subjecting relatively impure sugar, such as raw sugar, to a series of interrelated process steps in which dry heat is used in conjunction with selective control over proportions of sugar and syrup, characteristics of the syrup, and operations that take place incident to centrifugal separation of the sugar and syrup, all as described more specifically hereinafter. In its broader aspects the process of my invention involves the steps of mixing raw sugar with affination syrup, which is preferably hot and

saturated, or almost saturated, in its heated condition, in proportions such that a mass of a thick viscous consistency and having practically no liquid characteristics is produced, stirring the mass and adding dry heat thereto to raise its temperature and produce a magma of sufficient fluidity for centrifugal treatment and then subjecting the magma to treatment in centrifugal machines in a manner to separate the syrup from the sugar grain and to wash final quantities of adhering syrup from the grain. In addition, the process involves selective collection and handling of syrups flowing from the centrifugals in a manner to utilize their qualities to best advantage and to keep the process in continuous operation.

A significant feature of the present invention is that it combines the wetting and cleansing power of the affination syrup with the liquefying effect of dry heat so as to obtain the optimal advantages of both without requiring dissolution of sugar or the handling of large volumes of materials such as have attended the operation of prior processes. The proportion of syrup mixed with the sugar grain is governed not by the consistency of the mixture first to be formed but, instead, by the characteristics of the magma after a great deal of dry heat has been introduced thereinto. Thus in effect I dispense with a large amount of syrup and in its place substitute the liquefying effect of dry heat, utilizing the principle that a small proportion of constituent syrup at a high magma temperature will provide as great a liquefying and wetting effect as a very much larger quantity of syrup at the range of temperatures obtainable by simply mixing syrup with raw sugar.

Another important feature of a preferred embodiment of the invention is that the dissolution of sugar crystals is avoided substantially entirely by maintaining proper control over the dry substance and purity of the affination syrup in relation to the range of temperatures to which it is subjected. An affination syrup is preferably used which remains saturated or almost saturated throughout the operation of the process. When preheated saturated syrup is used to facilitate preliminary mixing with and wetting of the raw sugar, the heating of the mingled mass of sugar grain and syrup is controlled so that the temperature of the mass is not raised substantially above the original temperature of the syrup. By proper selection of the purity, temperature and dry substance of the syrup, the proportions of syrup and raw sugar mixed together, and the temperature to which the magma heat is raised, the maximum possible use may be made of dry heat and a magma of minimum density and maximum dry substance may be produced without danger of dissolving much sugar, which has been an inevitable result of the use of heat in prior processes. The only limit on the temperature to which the affination syrup and the magma can be raised is the limit imposed by the tendency of the syrup and magma to break down or caramelize when its temperature is raised too high.

In carrying out the process of my invention hot affination syrup and raw sugar are brought together at regulated rates of flow adapted to maintain the process in continuous operation, and the materials are mixed together, stirred and heated during passage toward centrifugals so that the consistency of the mass progressively changes from a thick viscosity similar to that of a mass of wet sand or heavy cement mortar to

a fluidity well suited for efficient centrifugal treatment, the latter condition being reached by the time charges of the magma are introduced into the centrifugals. During the centrifuging operations green liquor is thrown off the sugar grains and collected in a suitable receptacle, and a washing liquid is applied to the partly cleansed sugar to remove remaining adherent impurities, resulting in the production of wash syrup of relatively high purity as compared with the green liquor.

A further feature of a preferred embodiment of my invention is that the volume, purity and dry substance of the green syrup are kept within a range rendering it suitable for reuse as affination syrup by adding relatively pure syrup, such as the wash syrup above mentioned, thereto as needed, and the resulting syrup is continuously recirculated, reheated and remixed with additional untreated raw sugar in the first stage of the process. In this way the extracted syrup may be used over and over again as affination syrup, during periods of continuous operation of a week or more in duration, and not until discoloring or bacterial matter in the syrup has accumulated to an excessive extent is it necessary to discontinue its use in the process.

By the use of my process affination syrup may be used with completely satisfactory results which has a much lower purity than practicable heretofore. When the syrup is to be discarded from further affination uses it may be of a purity suited for treatment in a different manner than heretofore to recover further portions of its sugar content, thus instead of passing it through char filters, I may boil this discarded syrup into low grade remelt and use the run-off from the remelt to produce low grade massecuete. In this way the coloring matter accumulated in the affination syrup is eliminated without the use of char, resulting in important char savings and increased capacity of the char house for other liquors.

Still another advantageous feature of the improved process is that it results in pasteurization of the affination syrup and the raw sugar, so that bacteriological growth which may have taken place during storage and shipment of damp raw sugar may be curtailed, thus avoiding decomposition or inversion of sucrose through the action of such bacteria and preventing the growth of colloidal constituents which would interfere with filtration of the melted washed sugar.

A preferred type of apparatus for use in carrying out my improved affination process is illustrated diagrammatically in the accompanying drawing, and the ensuing description sets forth further details relating to the practice of the process by use of the illustrated or equivalent apparatus.

The apparatus shown in the drawing comprises a mixing trough 1 for preliminary mixing of the sugar and syrup, which is in the form of a long shallow trough having a convergent bottom in which is mounted a longitudinal shaft 2 carrying a scroll conveyor 3 and a series of mixing paddles 4 intermediate the volutions of the scroll. The sugar to be cleansed by the affination process, usually raw cane sugar of the kind produced in the tropics, is kept in a storage bin 6 from which it is withdrawn by gravity through a discharge chute 7 that may be regulated to govern the rate of flow of sugar from the bin into the mixer trough 1. Sugar passing through the discharge chute 7 enters the trough adjacent one end thereof, and into the same end of the trough

flows a stream of affination syrup from an overhead storage tank 8 or 8a. The syrup flows from the tank into the trough through a pipe 9 and valve controlled nozzles 9a, 9b, etc., and the total rate of flow may be controlled by a valve 10 so as to coordinate the flow of affination syrup with the flow of raw sugar and continuously introduce the syrup and sugar into trough 1 in suitable proportions to form a thick viscous mass having a consistency similar to that of wet sand.

The syrup storage tanks 8 and 8a are provided with heating means, for example, coils 11 and 11a, respectively, through which steam is circulated, in order to bring the affination syrup to the desired temperature before mixing it with the raw sugar. The tanks are also preferably provided with means for keeping the syrup in a state of agitation while it is being heated, suitable means of this type being in the form of pipes 12 and 12a, respectively, extending into each tank, through which compressed air is forced to agitate the syrup.

Although unsaturated affination syrup may be supplied from the storage tanks when starting the operation of my process, or on other special occasions when a departure from preferred operation may be dictated by convenience, I preferably use an affination syrup that remains saturated or almost saturated when heated to temperatures encountered in the process. For the best operating results I heat the syrup, before mixing it with the raw sugar, to a temperature in excess of 160° F. but below a point which would result in chemical changes, or in melting or decomposition of sugar grains during the mixing operation. The hot affination syrup, let us say at a temperature of 170° F., is preliminarily mixed with raw sugar from the bin 6 by the revolving conveyor and stirrer in the mixing trough 1. The flow of syrup and sugar is proportioned and maintained so as continuously to produce a thick mass having no appreciable liquid characteristics. With the sugar at an ordinary room temperature the mixing operation results in the production of a mass having a temperature somewhat higher than the original temperature of the sugar but a great deal lower than the original temperature of the syrup, 100° F. being typical. This mass of sugar and syrup is passed out of the mixing trough 1 through a discharge passage 5 at another end of the trough, and in so doing it travels between a pair of crushing rollers 15 which are spaced apart a slight distance in order to permit adequate flow of the material but to crush lumps that may be present in it as it leaves the mixing trough. After leaving the rollers 15 the mass drops into a mixing and conditioning tank 20 in which the further treatment is carried out in preparation for subsequent centrifuging operations.

The mixing and conditioning tank 20 is usually constructed in the form of an elongated trough having side walls and a bottom wall provided with outlet openings communicating with the usual gate-controlled chutes or goosenecks 28 for carrying the magma to centrifugal machines. In the illustrated form the tank has a relatively narrow downward extension 21 which is partly separated from a larger upper tank portion by inclined plates or deck members 22 forming a restricted passage or passages through which material may travel from the upper into the lower compartment. Just above the deck members and in the upper compartment is mounted a rotatable heating and stirring coil 23, and a similar

- rotatable heating and stirring coil 24 is mounted in the lower compartment adjacent the outlets above referred to and below the deck. By means of supply and return pipes 25 and 26, respectively, and a pump 27, heating fluid such as hot water is circulated through these rotatable coils. The heating fluid leaving the coils through pipe 26 enters and passes through a heater 28 which is controlled to maintain the fluid at a temperature not harmfully above the final temperature to which the magma is to be heated, and from heater 28 the fluid travels back to pump 27 through a conduit 29. The temperature and rate of flow of the fluid and the rate of rotation of the coils are regulated so as to introduce dry heat into the material in tank 20 in accordance with the requirements of the process, apparatus of well-known construction being used for such regulation.
- With the above described apparatus in operation for carrying out the improved affination process the thick mass of sugar and syrup introduced into the upper compartment of the tank moves downwardly therein as conditioned material is withdrawn through the chutes 28 for introduction into the centrifugal machines, and during its downward travel it first comes into contact with the revolving stirring and heating coil 23. The operation of this coil is such that it continuously maintains relative movement between the thick mass and its dry heating surfaces, and it keeps the mass in a state of continuous agitation so that heat transferred into the mass from the coil is thoroughly distributed throughout the portion thereof being subjected to treatment without danger of local overheating and caramelization. From the upper compartment of the tank, as material is withdrawn from below, the partially heated mass, which has now assumed a semi-liquid consistency and more closely resembles the usual magma, flows through the passage or passages in the deck plates 22 and then into contact with the stirring and heating coil 24 in the lower compartment. At this point the magma is subjected to further mixing and heating through action of the revolving coil 24, and the heat supplied from this coil brings the magma up to the desired temperature, which has been predetermined in accordance with the qualities of the materials, and imparts to it the degree of fluidity best suited for centrifuging treatments immediately to follow. The described conditioning of the magma also serves to remove impurities from the sugar crystals to an unusual degree.
- In the preferred practice of this process, if, as assumed, the affination syrup is mixed with the sugar at a syrup temperature of 170° F., the temperature and rate of flow of heating fluid through the coils 23 and 24 and the rate of rotation of the coils are controlled with reference to the rate at which magma is withdrawn from the tank for centrifuging so as to bring the magma to a temperature of approximately 160°-170° F. or higher before it leaves the tank through the chutes 28. The dry heat thus supplied to the magma renders the affination syrup and the magma highly fluid and softens the adherent film on the sugar crystals so that the crystals may be easily cleansed in the centrifugals.
- When a rapid flow of magma to the centrifugals is practicable, or when the affination syrup is not fully saturated, as may be the case if the syrup supply available to start the process is limited, I prefer to use stirring and heating coils for the

elements 23 and 24 which provide in excess of one square foot of heating surface for each cubic foot of magma being stirred and heated and to flow a heating fluid through the interior of the same and control the rate of movement of the magma relative to the heating surface so that the desired temperature may be imparted to the incoming magma within a period of only a few minutes, for example in less than ten minutes. Rapid heating in this way minimizes the dissolution of sugar grain by undersaturated syrup. In addition, it is of great importance where centrifuging operations are carried out rapidly, because of the greatly increased capacity thus imparted to the affination station. General aspects of this type of treatment are described in my United States Letters Patent No. 2,086,951 and Re. 20,556.

After the properly conditioned magma from chutes 28 is introduced into the centrifugals further improved operations are preferably carried out in order to obtain the greatest benefits from the previous treatments and to enable maintenance of the process on a continuous basis. The centrifugals employed in the final treatment of the magma embody the usual suspended basket 29 and surrounding curb or casing 31. They preferably are provided with automatic time controls for accurately governing the cycle of operations and the stages of the cycle at which a washing spray is turned on and off the sugar and the different grades of syrups flowing down the curb wall of each centrifugal are separated. Centrifugal apparatus including these features is shown and described in United States Letters Patent No. 2,145,633, of Eugene Roberts. The centrifugals also are preferably of the type especially adapted for operation at high speeds with very rapid acceleration to full speed in accordance with the process described in Eugene Roberts' application, Serial No. 113,542, filed December 1, 1936. For example, centrifugals of the kind described in United States Letters Patent No. 2,128,575 of Eugene Roberts, are particularly suited for such operation.

For the best results, hot magma introduced into the centrifugals is immediately subjected to strong centrifugal forces of the character produced by accelerating the usual 40" centrifugal to a speed in excess of 1250 R. P. M. in less than 40 seconds, and preferably to a speed of 1500 to 1600 R. P. M. in less than one minute, or 40 to 50 seconds. By subjecting the magma to centrifugal forces of this character within the period of time stated more than 90% of the syrup content of the magma is thrown away from the sugar crystals retained in the basket by the time the centrifugal has reached its full speed. Thereafter a spray of washing liquid, preferably water at a temperature in excess of 170° F., is directed against the walled-up sugar in the basket from a spray nozzle indicated at 33 in order to wash off the final portions of syrup which adhere to the crystals despite the strong forces adduced by the spinning operation. The wash water may be applied at any nozzle temperature below the point of objectionable steam formation, and it is preferably delivered from a spray nozzle having very fine orifices, under a pressure of about 25 to 35 pounds per square inch. This results in the production of a very fine hot mist that reaches the wall of sugar in the centrifugal uniformly and subjects the entire mass of sugar retained in the centrifugal to a very efficient cleansing action without dissolving the sugar to the extent heretofore encountered in the usual prior practice.

When following this preferred type of centrifuging operation, I am able to reduce the amount of sugar dissolved in the centrifugals by from 40 to 50% and to reduce to almost the same degree the volume of wash water and, correspondingly, the volume of wash syrup requiring expensive reprocessing for the recovery of the dissolved sugar. This improved centrifuging practice also yields a higher quality and color of sugar than has been obtainable in previous practices, and it shortens the cycle of the centrifugal operations and in that way largely increases the productive capacity of the centrifugals.

10 In order automatically to maintain the improved affination process on a continuously operating basis, I preferably employ centrifugals pro-

vided with means for effecting an accurate separation between the green and wash syrups flowing down the curb or casing 31 after being expelled from the revolving basket 29. A centrifugal embodying preferred means of this type is illustrated and described in the aforesaid Roberts Patent No.

2,145,633, and complete description of the apparatus is therefore unnecessary at this point. It suffices to state that the lower portion of the cas-

25 ing 31 for each centrifugal is provided with two concentric annular troughs 34 and 35 having separate off-take pipes 36 and 37, respectively. The green syrup expelled from the basket flows down

30 the inner wall of the casing 31, over an annular deflector 38 and into the inner trough 35. By the use of suitable time controls, after the green syrup and, if desired, a certain portion of the wash syrup has flowed into the inner trough 35 the deflector

35 38 is raised, and the remainder of the wash syrup is caught in the outer trough 34 so that it may be separately collected and subjected to separate subsequent treatment. The syrups received in off-takes 36 and 37 are carried to suitable separate

40 receptacles such as indicated at 40 and 41 through conduits 42 and 43, respectively. During passage through these conduits they are preferably treated with a neutralizing liquid, such as milk of lime, to overcome acidity. Milk of lime may be flowed

45 from a container 50 into a funnel 51 communicating with the conduit 43, the volume of flow being controlled by a valve 52 which is automatically regulated in response to the hydrogen ion concentration of the syrup entering receptacle 41 by

50 means of a pH control electrode 53 and a control mechanism of known construction indicated generally at 54.

It will be understood that the affination syrup expelled from the sugar by the centrifugals and 55 collected as "green syrup" has undergone a drop in purity and an increase in dry substance due to accretions of relatively impure and dry melas-

segenic material removed from the raw sugar.

The wash syrup is a more dilute but a purer 60 syrup, much purer than in processes used heretofore. By collecting a regulated portion of the wash syrup with the green syrup in each centrifuging cycle I compensate at least in part for the drop in purity of the green syrup without

65 substantially lowering its content of dry matter, and thus I automatically keep available in the green syrup receptacle a syrup that possesses the necessary characteristics for reuse as affination syrup in the process.

70 The syrup collected in the green syrup receptacle 41 is usually forced through a conduit 60 and into the affination syrup tank 8 by a pump 61. The wash syrup collected in receptacle 40 is forced into a "raw wash" tank 8a through a conduit 62 by a pump 63, and later filtered and

used in other processes. To permit flexibility in the make-up of the various syrups, conduits 60 and 62 communicate with the tanks 8a and 8, respectively, through branch pipes 64 and 65, and valves 66, 67, 68 and 69 are provided to enable the flow to be directed as desired. In addition, tank 8a communicates with the affination syrup pipe 9 through a conduit 70 controlled by a valve 71, and valve 72 is provided to permit regulation of the rate of flow from tank 8.

10 In the normal operation of my process the green syrup from the centrifugals, plus a regulated amount of wash syrup, is collected in receptacle 41, then pumped as required into tank 8 where it is reheated to the selected temperature, 15 and then flowed from tank 8 through pipe 9 at a regulated rate for mingling with raw sugar in the mixing trough 1. The remainder of the wash syrup, collected in receptacle 40, is valuable for further recovery of sugar, for example in remelt boilings or by filtering, passage through char and boiling into white masscicute. The affination syrup is recirculated in the described cycle over and over again, for periods of a week or longer, until it accumulates such a large amount of dis-

coloring matter that further use in the process is undesirable, whereupon it may be passed from tank 8 through a conduit 73 and used as syrup for low grade remelt pan boilings.

It is an important advantage of this process that it permits the use of affination syrup of a purity as low as 60, as well as of any purity above 60 which will result in the collection of excess syrup from the centrifugals of a selected purity best adapted for the operation of the particular refinery.

An example of the operation of the improved process at a typical cane sugar refinery is as follows:

At the beginning of a week of operations an available saturated remelt syrup having a purity of 60 to 75 and a Brix of not less than 80 is heated to about 180° F. and then continuously mixed with cold raw sugar in a mixing trough. For a 2000 ton daily melt of raw sugar about 3500 gallons of syrup is used to start the process. The initial mixture is a thick viscous mass having substantially no flow characteristics, at a temperature, depending upon the temperature of the raw sugar, usually not exceeding 115° F. This mass is passed through a mixing and conditioning tank of the character described above and heated to reach a temperature of 160-175° F. at the point of discharge to the centrifugals, the heating and mixing resulting in softening and loosening of the impure film on the sugar crystals and the formation of a highly fluid magma.

The heated magma is introduced into centrifugals during acceleration from 300 to 600 R. P. M. and spun to full speed of about 1500 R. P. M. in less than 50 seconds. When full speed has been attained over 90% of the syrup has been expelled, and a washing spray consisting of about 6 quarts of water or thin sweet syrup from char filters is then applied at about 180° F. and under 30 pounds pressure at the spray nozzle.

The green syrup from the centrifugals is kept at approximately constant density and purity by automatic addition of part of the wash syrup. It is maintained at a pH slightly above 7.0 by automatic addition of milk of lime, so that no appreciable increase in invert sugar occurs during a week of use. It is returned to an affination syrup storage tank, reheated and continuously recirculated as described above until the end of

the week, whereupon it is discarded and boiled into remelt.

The excess wash syrup has a purity 8 to 10 points higher than the green syrup, and its purity is increased 3 to 4 points by char filtering to yield a valuable syrup having a final purity of 85. The washed sugar, consisting of at least well-preserved crystals, attains a purity of 99.5.

Comparison of typical operating results of the improved affination process with the results of a process in use prior thereto provides a clearer understanding of the benefits flowing from the invention.

15		Improved process (with 40" flat bottom centrifugals; preferred centrifuging practices)	Prior process (with 40" flat bottom centrifugals of convention operation)	15
20	Amount of raw sugar of 98 purity.....	pounds.....	2,000,000 (1,000 tons)	2,000,000 (1,000 tons)
	Amount of affination syrup.....	do.....	570,000 (285 tons)	1,200,000 (600 tons)
	Dry substance (showing ratio of total syrup flow at head of process to total sugar) of syrup.....	80	71	20
	Temperature when mingled with sugar.....	°F.....	175	170

	Sugar in excess wash syrup to reprocess.....	do.....	150,000	300,000
30	Average purity of washed sugar.....	99.5	99	30

In addition to the benefits that are self-evident from a comparison of the above results, the increased purity of the washed sugar produced by the improved process and its greater freedom from colloidal materials greatly relieve the load on the char filter station by reducing the amount of discoloring impurities that must be carried through char filters and removed thereby after the sugar is remelted and by increasing the flow rate of the washed sugar liquor.

I wish it to be understood that the improved affination process is not restricted to use with any particular form of apparatus, nor to particular centrifuging practices. The details set forth in the foregoing specification concerning proportions, temperatures and other characteristics are given to enable ready adaptation of the invention to actual use and are not intended as restrictive except as required by a fair interpretation of the claims.

I claim:

1. The process of removing relatively impure adherent substantially dry syrup from grain sugar which comprises mixing the sugar with an affination syrup having a dry substance not substantially below 80 in proportions such as to produce a thick viscid mass unadapted for introduction into and purging in centrifugal machines, stirring the mass and adding dry heat thereto to raise its temperature to a point about 160° F. at which a magma of a fluidity sufficient to loosen the adherent dry syrup on the sugar grains and to be centrifuged effectively has formed, and then centrifuging the hot magma.

2. The process of removing relatively impure adherent substantially dry syrup from grain sugar which comprises mixing the sugar with syrup heated to a temperature above 160° F. and below a sugar caramelizing temperature and approximately saturated at such temperature in proportions such as to produce a thick viscid mass unadapted for introduction into and purging in centrifugal machines, stirring the mass and adding dry heat thereto until a magma of a fluidity

sufficient to loosen the adherent dry syrup on the sugar grains and to be centrifuged effectively has formed, and then centrifuging the hot magma.

3. The process of removing relatively impure adherent substantially dry syrup from grain sugar which comprises mixing the sugar with affination syrup heated to a temperature above 160° F. and below a sugar caramelizing temperature and approximately saturated at such temperature in proportions such as to produce a thick viscid mass unadapted for introduction into and purging in centrifugal machines, stirring the mass and increasing the temperature thereof to a point in

excess of 160° F. by adding dry heat thereto so as to produce a magma of sufficient fluidity for effective centrifuging, and then centrifuging the hot magma.

4. The process of removing relatively impure adherent substantially dry syrup from grain sugar which comprises mixing the sugar with affination syrup heated to a temperature above 160° F. and below a sugar caramelizing temperature and approximately saturated at such temperature in proportions such as to produce a thick viscid mass unadapted for introduction into and purging in centrifugal machines, stirring the mass and increasing the temperature thereof to a point in excess of 160° F. by adding dry heat thereto so as to produce a magma of sufficient fluidity for effective centrifuging, introducing successive charges of the hot magma into centrifugal machines and accelerating the same to a high speed to throw off the major portion of the syrup, and applying a spray of clear washing liquid at a temperature in excess of 170° F. to the sugar remaining in the centrifugal to remove the remaining adherent syrup.

5. The process of removing relatively impure adherent substantially dry syrup from grain sugar which comprises mixing the sugar with affination syrup heated to a temperature above 160° F. and below a sugar caramelizing temperature and approximately saturated at such temperature in proportions such as to produce a thick viscid mass unadapted for introduction into and purging in centrifugal machines, stirring the mass and increasing the temperature thereof to a point in excess of 160° F. by adding dry heat thereto so as to produce a magma of sufficient fluidity for effective centrifuging, introducing successive charges of the hot magma into centrifugal machines, accelerating the centrifugals to expel the major portion of the syrup from the sugar grains, applying a spray of wash water to the sugar remaining in the centrifugal to remove the remaining adherent syrup, collecting the expelled syrup together with a portion of the wash syrup

separately from the remainder of the wash syrup, and recirculating the combined syrups for heating and reuse as affination syrup as aforesaid.

6. Affination process for refining raw cane sugar which comprises continuously combining a stream of raw sugar and a stream of affination syrup having a dry substance not substantially below 80 in proportions regulated to form a thick non-flowing mass initially having a temperature not exceeding 115° F., continuously passing the mass into a mixing tank, stirring the mass and converting it into a magma of fluid consistency having a temperature in excess of 160° F. while in said tank by adding dry heat thereto, withdrawing the fluid magma from the tank and immediately centrifuging the same.

7. Affination process for refining raw cane sugar which comprises continuously combining a stream of raw sugar and a stream of affination syrup having a dry substance not materially below 80 and a temperature above 160° F. in proportions regulated to form a thick non-flowing mass, continuously passing the mass into a mixing tank adjacent centrifugal machines, stirring the mass and converting it into a magma of fluid consistency having a temperature in excess of 160° F. by maintaining relative movement between the same and surfaces heated to a temperature not harmfully in excess of the maximum temperature to which the mass is to be heated and providing in excess of one square foot of heating surface for each cubic foot of the mass being stirred and heated, withdrawing the fluid magma from the tank and immediately centrifuging the same.

8. The process of claim 13, washing the material during centrifuging with a washing liquid after all but a small proportion of the syrup has been purged therefrom, combining green syrup expelled during the centrifuging of the magma with regulated proportions of the resulting wash syrup to form a combined syrup of approximately the same purity and density as said affination syrup, adding an alkalizing agent to the syrup in an amount regulated to avoid excess acidity, and repeatedly recirculating and using such combined syrup as affination syrup as aforesaid.

9. Affination process for refining raw sugar which comprises mixing raw sugar with affination syrup of approximately predetermined purity and density in proportions to form a thick non-flowing mass, converting the mass into a magma having a fluidity suitable for effective centrifuging by adding dry heat, centrifuging the magma, continually combining green syrup and wash syrup at the centrifugals and forming a combined syrup of approximately the same purity and density as said affination syrup, continually producing washed sugar and excess wash syrup of relatively high and approximately constant purities at the centrifugals, mixing said combined syrup and the impurities corralled therein with additional raw sugar as affination syrup as aforesaid, and passing said washed sugar and excess wash syrup onward for further refining operations.

10. Affination process for refining raw cane sugar which comprises continually mixing raw sugar with affination syrup of approximately constant purity and density in fixed proportions regulated to form a thick heavy mass, continually flowing the mass to a point adjacent centrifugal machines and converting the same into a magma

of substantially constant, predetermined temperature and fluidity during passage to said point by stirring and adding dry heat to the same, continually subjecting successive portions of said magma to uniform purging and washing operations in the centrifugal machines, continually combining green syrup and a predetermined amount of wash syrup expelled at the centrifugal machines and forming a combined syrup of approximately the same purity as said affination syrup and continually recovering washed sugar and another syrup, consisting of the remainder of said wash syrup, of approximately constant and relatively high purities from said machines.

11. Affination process for refining raw cane sugar which comprises mixing raw sugar of purity ranging between 94 and 98 with less than one-third by weight of affination syrup having a dry substance not substantially below 80, a purity considerably below 80 and a temperature in excess of 160° F., stirring the resulting mass and heating the same to a temperature in excess of 160° F. to form a magma having a fluidity suited for efficient centrifuging, centrifuging successive portions of the magma and recovering washed sugar from the centrifugals having a purity of at least 99.5.

12. Affination process for refining raw sugar which comprises forming a magma consisting of raw sugar in admixture with affination syrup of predetermined purity, centrifugally purging syrup from the sugar, applying washing liquid to the sugar after most of the syrup has been purged therefrom, flowing a predetermined portion of the resulting wash syrup into the green syrup purged from the sugar to form a combined syrup of approximately the same purity as said affination syrup, using said combined syrup for affination as aforesaid, and collecting the remainder of said wash syrup separately and passing the same onward for further processing.

13. The process of removing adherent surface impurities from grain sugar which comprises forming a viscous non-flowing mass consisting of grain sugar to be refined in admixture with less than one-third by weight of at least approximately saturated affination syrup, stirring the mass and adding dry heat thereto until a magma having a temperature and fluidity suited for loosening the adherent impurities on the sugar grain and for effective centrifuging has formed, and then centrifuging the heated magma, said affination syrup as admixed with the grain sugar having a content of dry substance such that it remains at least approximately saturated at a temperature corresponding to the centrifuging temperature of the magma.

14. The process of removing adherent surface impurities from grain sugar which comprises forming a viscous non-flowing mass consisting of grain sugar in admixture with saturated affination syrup, stirring the mass and adding dry heat thereto until a magma having a temperature and fluidity suited for loosening the adherent impurities on the sugar grain and for effective centrifuging has formed, and then centrifuging the heated magma, said affination syrup as admixed with the grain sugar having a content of dry substance such that it remains at least approximately saturated at a temperature corresponding to the centrifuging temperature of the magma.

GEORGE E. STEVENS.

CERTIFICATE OF CORRECTION.

Patent No. 2,175,998.

October 10, 1939.

GEORGE E. STEVENS.

It is hereby certified that error appears in the printed specification of the above numbered patent requiring correction as follows: Page 5, second column, line 22, for "masseciute" read massecuite; page 6, first column, line 7, strike out the words "at least" and insert the same before "99.5" in line 8; page 6, first column, in the table, lines 3 and 4 thereof, strike out "(showing ratio of total syrup flow at head of process to total sugar)" and insert the same after "syrup" in line 2 of said table; line 61, claim 1, for "about" read above; and second column, line 70, claim 5, after "centrifugals" insert rapidly; and that the said Letters Patent should be read with this correction therein that the same may conform to the record of the case in the Patent Office.

Signed and sealed this 26th day of December, A. D. 1939.
